ABSTRACT

A control system and method controls the hydrocarbon of recycle acid in an alkylation unit to maintain a predetermined hydrocarbon content. The hydrocarbon content is controlled by controlling the interface level between the acid phase and the hydrocarbon phase in an acid settler in accordance with sensed densities of fresh acid entering the alkylation unit, crude alkylate provided by the acid settler in the alkylation unit and the recycle acid. A network substantially determines the actual hydrocarbon content of hydrocarbon enriched acid leaving the acid settler a portion of which is provided as the recycle acid, along with the fresh acid, to a contactor. In the contactor, an isoparaffin and an olefin are contacted with the acid to provide an acid-hydrocarbon mix to the acid settler. The settler provides the crude alkylate for further processing.

SHEET 2 OF 2

FIG. 2

MEANS AND METHOD FOR CONTROLLING THE HYDROCARBON CONTENT OF RECYCLE ACID IN AN ALKYLATION UNIT

BACKGROUND OF THE INVENTION

1. Field of the Invention

The system of the present invention relates to control systems and methods in general and, more particularly, to a control system and method for an alkylation unit.

2. Description of the Prior Art

Heretofore, level control systems for acid settlers controlled the interface level in an acid settler to a predetermined value. As the composition of the olefin and isoparaffin feed changed or the temperature changed, the hydrocarbon content of recycle acid from the settler changed accordingly and differed from that normally provided by the predetermined interface level.

The present invention controls the interface level in the acid settler as a function of the hydrocarbon content of the hydrocarbon enriched acid leaving the settler. In doing so, the system senses the densities of the hydrocarbon enriched acid, the crude alkylate and the fresh acid which are used to determine the hydrocarbon content of the hydrocarbon enriched acid.

SUMMARY OF THE INVENTION

A system controls the interface level between the acid phase and the hydrocarbon phase in an acid settler in an alkylation unit. The settler receives an acid-hydrocarbon mix from a contactor which has reacted an olefin and an isoparaffin in the presence of an acid catalyst. The settler provides crude alkylate and hydrocarbon enriched acid a portion of which is recycled to the contactor. A portion of the hydrocarbon enriched acid from the settler is discharged and replaced by fresh acid entering the alkylation unit. The control system includes sensors sensing conditions of the fresh acid, the crude alkylate and the recycle acid. A network provides a signal corresponding to the hydrocarbon content of the recycle acid in accordance with the sensed conditions. A control signal is developed in accordance with the hydrocarbon content signal and a signal corresponding to a predetermined hydrocarbon content. The control signal is applied to control means which control the interface level in the settler so as to control the hydrocarbon content of the recycle acid.

The objects and advantages of the invention will appear more fully hereinafter from a consideration of the detailed description which follows, taken together with the accompanying drawings wherein one embodiment of the invention is illustrated by way of example. It is to be expressly understood, however, that the drawings are for illustration purposes only and are not to be construed as defining the limits of the invention.

DESCRIPTION OF THE DRAWINGS

FIG. 1 includes a simple block diagram of a control system, constructed in accordance with the present invention, for controlling the hydrocarbon content of recycle acid in an alkylation unit which is also shown in partial schematic form.

FIG. 2 is a simplified block diagram of the set point signal means shown in FIG. 1.

DESCRIPTION OF THE INVENTION

Referring to FIG. 1, there is shown a portion of an alkylation unit in which an olefin is reacted with an isoparaffin in the presence of a catalyst, such as sulphuric acid or hydrofluoric acid, and which is hereinafter referred to as acid, to form a higher molecular weight isoparaffin. For purpose of explanation, the acid in the following description shall be sulphuric acid. The olefin may be butylenes, propylene, or a mixture of butylenes and propylene, while the isoparaffin may be isobutane.

The olefins and isoparaffin enter a contactor 4, by way of a line 6, where the olefin and isoparaffin are contacted with recycle acid entering by way of a line 7. Contactor 4 provides an acid-hydrocarbon mix by way of a line 8 to an acid settler 12. Settler 12 separates crude alkylate from the acid and the hydrocarbon product is provided through a line 14 while the acid is removed by way of a line 16. It should be noted that the acid from settler 12 is an acid which is enriched with some hydrocarbon that has not been thoroughly separated by the action of settler 12. Acid settler 12 may be the only acid settler in the unit or it may be any acid settler in a group of acid settlers. Inside acid settler 12, a hydrocarbon phase is separated from an acid phase by an interface level. Fresh acid enters line 16 by way of a line 17 as needed to maintain a desired acid strength. A pump 20 pumps the acid from line 16 into line 7. A portion of the acid in line 7 is discharged by way of a line 21 leaving the recycle acid to be provided to contactor 4. The discharged acid may be provided to another alkylation unit or disposed of.

The crude alkylate in line 14 can have its octane rating increased by increasing the amount of hydrocarbon in the acid leaving settler 12. There are several variables that could affect the hydrocarbon in line 16. One variable is settler 12 interface level between the acid phase and the hydrocarbon phase. Another variable is the temperature within settler 12. The type and quantity of the olefins in line 6 will also affect the hydrocarbon content in the recycle acid in line 16.

In practice it may not be feasible to maintain the various variables at constant values. Hence, the control of the interface level in settler 12 at a constant value will not necessarily maintain the hydrocarbon content in the recycle acid in line 16 at a constant value. It is therefore desirable to control the interface level in acid settler 12 as a function of the hydrocarbon content of the recycle acid in line 16.

The hydrocarbon content of the recycle acid in line 16 can be related to the density of the recycle acid in line 16, the density of the acid portion of the recycle acid and the density of the hydrocarbon portion of the recycle acid by the following equation 1.

$$H_B = 100 (D_A - D_B) / (D_A - D_H) \quad (1)$$

where H_B is the determined recycle acid hydrocarbon content in volume percent, D_A , D_H and D_B are the densities of the acid portion of the recycle acid, the hydrocarbon portion of the recycle acid and of the recycle acid itself.

Equation 1 presumes that there is no volume mixing effect from combining the acid and the hydrocarbon portions of the recycle acid; thus, it presumes that combining X volume units of acid with Y volume units of hydrocarbon will result in $(X + Y)$ volume units of mix-

ture. Although this may not be exactly true in practice, the error introduced by this approximation does not materially affect the application of the invention.

Since fluid density is a function of temperature, it is necessary that all density values be adjusted to a common temperature base, such as 60° F, before determining existing recycle acid hydrocarbon content from equation 1.

The interface level in settler 12 is also affected by a valve 25 in line 21 cooperating with a flow rate sensor 26 and a flow recorder controller 27. The set point of flow recorder controller 27 may be preset for a predetermined flow rate. Sensor 26 provides a signal to controller 27 corresponding to the actual flow rate in line 21. Flow rate recorder controller 27 then provides a signal to valve 25 to control the flow rate so that the flow rate in line 21 assumes the flow rate as indicated by the position of the set point of controller 27. The discharge acid flow rate is maintained at a value so that the interface level may be controlled by controlling the fresh acid flow rate as hereinafter explained.

Density analyzers 30, 31 and 33 provide signals E_1 , E_2 , and E_3 , respectively, corresponding to the density of the recycle acid in line 7, to fresh acid in line 17 and the crude alkylate in line 14, respectively. The fresh acid density is used as the density of the acid portion density D_A of the recycle acid, while the crude alkylate density is used as the hydrocarbon portion density D_H . Density analyzers 30, 31, 33 may by way of example be devices manufactured by Automation Products Incorporated under the name Dynatrol Density-Specific Gravity Control Device. The devices are adjustable to control the range of operation. For example, analyzer 31 might include a range and span of 1.5 to 2.0 specific gravity units at an operating temperature range of 45° to 70° F. While density analyzer 30 may have a specified range and span of 1.34 to 1.84 specific gravity units and density analyzer 33 may have a specified range and span of 0.5 to 1.0 specific gravity units.

A conventional type level sensor 40 provides a signal E_4 corresponding to the interface level to a level recorder controller 41, which may be of a conventional type, and a set point signal means 45 which also receives signals E_1 , E_2 and E_3 . Set point signal means 45 provides a control signal E_5 to level recorder controller 41 to adjust its set point, accordingly. In accordance with signals E_1 through E_4 , equation 1 and other limitations herinafter described the set point is changed accordingly. Level recorder controller 41 controls the interface level in settler 12 as follows: When the interface level in settler 12 is greater than the level determined by the position of the set point in controller 41, controller 41 provides a signal to a valve 49 in line 17 reducing the flow rate of the fresh acid in line 17. Since the discharge acid flow rate is at a constant rate, the acid provided to contactor 4 is reduced and hence the acid to settler 12 is thereby reduced until such time as the interface level in settler 12 is substantially equal to the level determined by the position of the set point in controller 41.

When the interface level in settler 12 is less than the level as determined by the position of the set point in controller 41, controller 41 provides a signal to valve 49 increasing the flow rate of the fresh acid in line 17 thereby increasing the acid entering contactor 4 and acid settler 12 which results in the interface level in settler 12 increasing until such time it is substantially

equal to the level as determined by the position of the set point in controller 41.

Referring to FIG. 2, set point signal means 45 is placed in operation by the closure of a conventional type on-off toggle switch 55. When closed, switch 55 passes a direct current voltage V_1 from a source 56 of direct current voltages to clock means 58 thereby energizing clock means 58 causing it to provide sampling pulses E_8 on a periodic basis. Source 56 also provides direct current voltages V_2 through V_8 . Sampling pulses E_8 are applied to sample and hold circuits 60, 60A and 60B causing them to sample and hold signals E_1 through E_3 , respectively. Elements having a suffix are connected and operate in a similar manner as elements having the same number without a suffix. Subtracting means 63 subtracts the output from sample and hold circuit 60 from the output from sample and hold circuit 60A to provide a signal corresponding to the term $(D_A - D_B)$ in equation 1. Similarly, subtracting means 63A subtracts the output provided by sample and hold circuit 60B from the output provided from sample and hold circuit 60A to provide a signal corresponding to the term $(D_A - D_H)$. A divider 65 divides the signal from subtracting means 63 with the signal from subtracting means 63A to provide an output which is multiplied with voltage V_2 by a multiplier 68. Voltage V_2 corresponds to the term 100 in equation 1. Multiplier 68 provides a signal E_9 corresponding to the determined hydrocarbon content H_B of the recycle acid in line 16 and 7.

A required change ΔL in the interface level so that the hydrocarbon content of the recycle acid is substantially equal to a target hydrocarbon content is determined from equation 2:

$$\Delta L = e(H_B - H_T)$$

where e is a constant, and may have a value of -0.5, and H_T is the target hydrocarbon content.

Voltage V_3 , corresponding to a target hydrocarbon content of the recycle acid H_T is subtracted from signal E_9 by subtracting means 75 to provide a signal corresponding to the term $(H_B - H_T)$ in equation 2. A multiplier 77 multiplies voltage V_4 with the signal from subtracting means 75 to provide a signal E_{10} corresponding to the term ΔL in equation 2.

The change in the interface level required to achieve the desired level may in itself have some limitations placed on it. In order to prevent large and rapid changes in settler interface level and hydrocarbon content of the recycle acid which could upset smooth operation of the alkylation unit, a limitation is placed on the amount which the settler level can be changed at one time. In this regard, voltage V_5 , which is positive, and voltage V_6 , which is negative, correspond to the largest increase in settler level ΔL_U which will be permitted and to the largest decrease in settler level ΔL_L which will be permitted, respectively. Comparators 80, 80A compare signal E_{10} with voltages V_5 and V_6 , respectively. For the condition that the required change in the interface level does not equal or exceed a limit, comparators 80, 80A provide high level direct current outputs which cause an AND gate 81 to provide a high level direct current output to an electronic switch 83. Switch 83 is rendered conductive by the high level output from AND gate 81 and passes signal E_{10} from multiplier 77 as a change signal E_{11} . The high level outputs from comparators 80, 80A are inverted to low levels by

inverters 85 and 85A, respectively, to render electronic switches 83A and 83B, respectively, nonconductive. While non-conductive switches 83A, 83B block voltages V_5 and V_6 , respectively.

When the required change exceeds the upper change limit ΔL_U , the upper change limit is used as the change to the interface level. Thus, under the last mentioned condition, comparator 80 provides a low level output which is inverted to a high level by an inverter 85 to render switch 83A conductive. When rendered conductive, electronic switch 83A passes positive voltage V_5 as change signal E_{11} . Comparator 80A provides a high level output, which is inverted to a low level by inverter 85A thereby rendering switch 83B non-conductive to block voltage V_6 . AND gate 81 provides a low level output in response to the output from comparator 80 causing switch 83 to block signal E_{10} .

When the required change is a reduction in level equal to or greater than lower change limit ΔL_L , the lower change limit is used as the change to the interface level. Under the last mentioned condition, comparators 80, 80A provide a high level output and a low level output, respectively. Inverters 85 and 85A provide a low level output and a high level output, respectively, thereby rendering switch 83A non-conductive and switch 83B conductive, respectively. Switch 83B when rendered conductive passes negative voltage V_6 as signal E_{11} . AND gate 81 provides a low level output in response to the output from comparator 80A causing switch 83 to block signal E_{10} . The inverted output from comparator 80 causes switch 83A to block voltage V_5 .

A desired interface level is determined by algebraically summing change level signal E_{11} with the sensed interface level signal E_4 which is accomplished by summing means 90. Summing means 90 provides a signal E_{12} corresponding to the desired interface level to comparators 93, 93A. Comparators 93, 93A also receive voltages V_7 and V_8 , respectively, corresponding to an upper limit L_U and a lower limit L_L , respectively, for the interface level in settler 12. Voltage V_7 is more positive than voltage V_8 . When the desired level E_{12} is less than the upper level limit and greater than the lower level limit, comparators 93, 93A provide high level direct current outputs to an AND gate 97 and to inverters 98, 98A. The high level outputs cause AND gate 97 to provide a high level direct current output to an electronic switch 100 rendering it conductive. Switch 100 when rendered conductive passes signal E_{12} as a new set point signal E_{14} . Inverters 98, 98A invert the high level outputs from comparators 93, 93A, respectively, to a low level rendering electronic switches 100A and 100B non-conductive. When rendered non-conductive switches 100A and 100B block voltages V_7 , V_8 , respectively.

For the condition that the desired interface level is equal to or greater than the upper level limit, the upper limit is used as the new interface level. Under the last mentioned condition, comparator 93 and 93A provide a low level output and a high level output, respectively. The output from comparator 93 causes AND gate 97 to provide a low level output to switch 100 rendering it non-conductive. Switch 100 when non-conductive blocks signal E_{12} . Inverter 98 inverts the low level output from comparator 93 to a high level to render switch 100A conductive thereby providing voltage V_7 as signal E_{14} . The high level output from comparator 93A is in-

verted to a low level by inverter 98A causing it to render switch 100B non-conductive to block voltage V_8 . For the condition that the desired level is equal to or less than the lower limit level L_L , the lower level limit is used as the new interface level. Under the last mentioned condition, comparators 93, 93A provide a high level output and a low level output, respectively. AND gate 97, in response to the low level output from comparator 93A, provides a low level output to switch 100 rendering it non-conductive to block signal E_{12} . The high level output from comparator 93 is inverted to a low level to render switch 100A non-conductive thereby blocking voltage V_7 . The low level output from comparator 93A is inverted to a high level by inverter 98A rendering switch 100B conductive to pass voltage V_8 as signal E_{14} .

Signal E_{14} is applied to a sample and hold circuit 110. Sample and hold circuit 110 is controlled so that it will sample and hold signal E_{14} at a predetermined time after the sampling and holding of signals E_1 , E_2 , and E_3 by circuits 60, 60A and 60B, respectively, to allow for the aforementioned computations to be made. Clock means 58 provides a pulse E_8 to a one-shot multivibrator 112. Multivibrator 112 acts as a time delay, the time delay being the width of the pulse provided by multivibrator 112. The trailing edge of the pulse from multivibrator 112 is triggered to another one-shot multivibrator 114. Multivibrator 114 when triggered provides a sampling pulse to sample and hold circuit 110 causing it to sample and hold signal E_{14} . Sample and hold circuit 110 provides signal E_5 to level recorder controller 41 to adjust the set point in controller 41.

The control of interface level in settler 12 has been heretofore described by controlling the flow rate of the fresh acid. It would be obvious to one skilled in the art, that the interface level may also be controlled by controlling the flow rate of the discharge acid while maintaining a constant flow rate for the fresh acid.

40 A digital computer may be used in lieu of set point signal means 45. It is necessary that signals E_1 through E_4 be converted to digital signals, which may be done by a conventional type analog-to-digital converters. The digital signals are applied to a general purpose digital computer, which may be of a conventional type. The digital computer is programmed to solve equations 1, 2 and to carry out the selective functions with respect to the interface level change and the interface level, (i.e., ΔL , ΔL_U or ΔL_L and L , L_U or L_L). The digital output from the digital computer corresponding to the desired interface level is converted by a conventional digital-to-analog converter. The digital-to-analog converter provides signal E_5 to flow recorder controller 41 to control the interface level in acid settler 12 as heretofore explained.

60 The system of the present invention as heretofore described maintains the hydrocarbon content of recycle acid in an alkylation unit, by controlling the interface level between the acid phase and hydrocarbon phase in an acid settler in the alkylation unit. The level in the settler is controlled as a function of the determined hydrocarbon content of the recycled acid. The hydrocarbon content of the recycled acid is determined from the density of fresh acid entering the alkylation unit of the recycle acid and of crude alkylate provided by the settler.

65 What is claimed is:

1. A system for controlling an alkylation unit to maintain the hydrocarbon content of recycle acid in the alkylation unit and said alkylation unit includes a contactor wherein an olefin-isoparaffin mixture is contacted with acid and the contactor provides an acid-hydrocarbon mixture to an acid settler which separates a hydrocarbon phase from an acid phase to provide hydrocarbon enriched acid and provide crude alkylate, a portion of the hydrocarbon enriched acid is discharged while a portion of the hydrocarbon enriched acid is recycled back to the contactor as the recycle acid along with fresh acid entering the alkylation unit, comprising means for sensing conditions of the fresh acid, the crude alkylate and the recycle acid and providing a signal corresponding to the hydrocarbon content of the recycle acid in accordance with the sensed conditions, means for providing a signal corresponding to a predetermined hydrocarbon content for the recycle acid, means connected to the sensing means and to the predetermined hydrocarbon content signal means for providing a control signal corresponding to a desired interface level between the acid phase and the hydrocarbon phase in the acid settler, and means connected to the control signal means for controlling the interface level in the acid settler in accordance with the control signal so as to control the hydrocarbon content of the recycle acid.

2. A system for maintaining a predetermined hydrocarbon content for recycle acid in an alkylation unit and said alkylation unit includes a contactor wherein an olefin-isoparaffin mixture is contacted with acid and the contactor provides an acid-hydrocarbon mixture to a settler which separates a hydrocarbon phase and an acid phase to provide hydrocarbon enriched acid and crude alkylate, fresh acid entering the alkylation unit is added to the hydrocarbon enriched acid, a portion of the hydrocarbon enriched acid is discharged while a portion of the hydrocarbon enriched acid is recycled back to the contactor along with the fresh acid as the recycle acid, comprising means for sensing conditions of the fresh acid, the crude alkylate and the recycle acid, means for sensing an interface level between the acid phase and the hydrocarbon phase in the settler, means for providing a signal corresponding to a predetermined target hydrocarbon content for the recycle acid, means for controlling the interface level in the settler in accordance with a control signal, and means connected to the sensing means, to the target hydrocarbon content signal means and to the control means for providing the control signal to the control means in accordance with the condition signals, the sensed level signal and the target hydrocarbon content signal to control the hydrocarbon content of the recycle acid.

3. A system as described in claim 2 in which the condition sensing means senses the densities of the fresh acid, the crude alkylate and the recycle acid and provides corresponding signals.

4. A system as described in claim 3 in which the control signal means includes means connected to density sensing means for providing a signal corresponding to the hydrocarbon content of the recycle acid in accordance with the density signals and the following equation:

$$H_B = 100(D_A - D_H) / (D_A - D_H)$$

where H_B is the hydrocarbon content of the recycle acid and D_A , D_B and D_H are the densities of the fresh

acid, the recycle acid and the crude alkylate; means connected to the hydrocarbon content signal means and to the target signal means for providing a signal corresponding to a change ΔL in the interface level in the settler in accordance with the hydrocarbon content signal and the target signal and the following equation:

$$\Delta L = e(H_B - H_T)$$

10 where e is a constant and H_T is the target hydrocarbon content; and means connected to the change signal means, to the level sensing means and to the control means for summing the change signal and the sensed level signal to provide a signal corresponding to a desired interface level in the settler as the control signal.

15 5. A system as described in claim 4 further comprising means for providing reference signals corresponding to upper ΔL_U and lower ΔL_L limits on the amount 20 of change in the interface level in the settler and upper L_U and lower L_L limits on the interface level in the settler; the change signal means further comprises first switching means connected to the summing means and receiving the change ΔL signal and the ΔL_U and ΔL_L 25 reference signals for providing the ΔL signal as the change signal to the summing means when the change ΔL is less than the upper ΔL_U limit but greater than the lower ΔL_L limit, providing the ΔL_U reference signal as the change signal to the summing means when the change ΔL is not less than the upper ΔL_U limit, and providing the ΔL_L reference signal as the change signal to the summing means when the change ΔL is not greater than the lower ΔL_L limit; and the summing means further comprises second switching means connected to the control means and receiving the desired level signal from the summing means and the L_U and L_L reference 30 signals from the reference signal means for providing the desired level signal to the control means at the control signal when the desired level is less than the upper level limit L_U and greater than the lower level limit L_L , providing the L_U reference signal to the control means as the control signal when the desired level signal is not less than the upper level limit L_U and providing the L_L reference signal to the control means as the control signal when the desired level signal is not greater than the lower level limit L_L .

35 6. A method for controlling an alkylation unit to control the hydrocarbon content of recycle acid in the alkylation unit and said alkylation unit includes a contactor wherein an olefin-isoparaffin mixture is contacted with acid and the contactor provides an acid-hydrocarbon mixture to an acid settler which separates a hydrocarbon phase and an acid phase to provide hydrocarbon enriched acid and crude alkylate, a portion of the hydrocarbon enriched acid is discharged while a portion of the hydrocarbon enriched acid is recycled back to the contactor as the recycle acid along with fresh acid entering the alkylation unit, which comprises the following steps of sensing conditions of the fresh acid, the crude alkylate and the recycle acid, sensing an interface level between the acid phase and the hydrocarbon phase in the acid settler, providing a signal corresponding to a predetermined hydrocarbon content for the recycle acid, controlling the interface level in the acid settler in accordance with a control signal, providing the control signal in accordance with the condition signals, the level signal and the target hydrocarbon

contents signal for acid control the hydrocarbon content of the recycle acid.

7. A method as described in claim 6 in which the sensed conditions are the densities of the fresh acid, the crude alkylate and the recycle acid.

8. A method as described in claim 7 in which the control signals step include providing a signal corresponding to the hydrocarbon content of the recycled acid in accordance with the density signals and the following equation:

$$H_B = 100(D_A - D_B)/(D_A - D_H)$$

where H_B is the hydrocarbon content of the recycle acid and D_A , D_B and D_H are the densities of the fresh acid, the recycle acid and the crude alkylate; providing a signal corresponding to a change ΔL in the interface level in the acid settler in accordance with the hydrocarbon content signal and the target signal and the following equation:

$$\Delta L = e(H_b - H_T)$$

where e is a constant and H_T is the target hydrocarbon content; and summing the change signal and the sensed interface level signal to provide a signal corresponding to a desired interface level in the acid settler as the con-

trol signal.

9. A method as described in claim 8 which further comprises the following steps, providing reference signals corresponding to upper ΔL_U and lower ΔL_L limits 5 on the amount of interface level change and upper L_U and lower L_L limits on the interface level in the acid settler; and the change signal step further comprises providing the ΔL signal as the change signal when the change ΔL is less than the upper ΔL_U limit but greater than the lower ΔL_L limit, providing the ΔL_U reference signal as the change signal when the change ΔL is not less than the upper ΔL_U limit and providing the ΔL_L reference signal as the change signal when the change ΔL is not greater than the lower ΔL_L limit; and the summing step further comprises comparing the sum signal with the L_U and L_L reference signals, providing the sum signal as the control signal when the sum signal is less than the upper level limit L_U and greater than the lower level limit L_L , providing the L_U reference signal as the control signal when the sum signal is not less than the upper level limit L_U and providing the L_L reference signal as the control signal when the sum signal is not greater than the lower level limit L_L .
